(57) CLAIM

The ornamental design for a hoist cover as shown and described.

DESCRIPTION

FIG. 1 is a perspective view of a hoist cover, showing our new design;

FIG. 2 is another perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the drawings depict portions of the hoist cover that form no part of the claimed design. The broken line showing of a hoist in FIG. 1 depicts environment that form no part of the claimed design. The dash-dot broken lines in the drawings define boundaries of the claimed design and form no part of the claimed design.
